UNITED STATES PATENT OFFICE

164,785

ANIMATED FIGURE TRUNDLE TOY

Alex Lustig, New York, N. Y.

Application October 14, 1949, Serial No. 5,480

Term of patent 3½ years

(Cl. D34—15)

To all whom it may concern:

Be it known that I, Alex Lustig, a citizen of the United States of America, residing in New York city, county of New York, and State of New York, have invented a new, original, and ornamental Design for an Animated Figure Trundle Toy, of which the following is a specification, reference being had to the accompanying drawing, forming part thereof, wherein,

Figure 1 is a front perspective view of an animated figure trundle toy showing my new design with the moving parts in one position.

Figure 2 is a rear elevational view of the animated figure trundle toy in the position shown in Figure 1.

Figure 3 is a rear elevational view thereof with the handle member removed for convenience of illustration, and showing the animated figure trundle toy in another position.

I claim:

The ornamental design for an animated figure trundle toy, substantially as shown and described.

ALEX LUSTIG.
